UNITED STATES PATENT OFFICE.

FREDERICK M. FURBER, OF REVERE, MASSACHUSETTS, ASSIGNOR TO UNITED SHOE MACHINERY CORPORATION, OF PATERSON, NEW JERSEY, A CORPORATION OF NEW JERSEY.

APPARATUS FOR TREATING SHOE MATERIALS.

Application filed September 20, 1924. Serial No. 738,883.

To all whom it may concern:

Be it known that I, FREDERICK M. FURBER, a citizen of the United States, residing at Revere, in the county of Suffolk and Commonwealth of Massachusetts; have invented 5 certain Improvements in Apparatus for Treating Shoe Materials, of which the following description, in connection with the accompanying drawings, is a specification, 10 like reference characters on the drawings indicating like parts in the several figures.

This invention relates to apparatus for heating shoe materials with or without moist vapor. For example, in the manufacture of 15 boots and shoes it is common to heat the toes with hot, moist vapor at two stages to render the materials soft and pliant, first for the pulling-over operation, and second, for the lasting operation. The treatment is substantially the same at both of these stages 20 but the apparatus for the first treatment is usually designed to treat the materials in a flat condition, whereas that for the second usually has a housing into which the toe end 25 of one or more pulled-over shoes may be inserted for treatment.

A difficulty experienced in such treating with many of the apparatus heretofore in use is that if the softening effect is rapid 30 enough to keep pace with the subsequent operations the upper leather is too often scorched or stained, particularly when the period of treatment is prolonged beyond the allotted time. In any event, the quantity of 35 waste vapor discharged into the atmosphere is usually so great as to be a serious menace to health and machinery.

In view of the above-mentioned conditions 40 an object of the present invention is to provide an improved apparatus adapted to treat shoe materials with heat and moist vapor so that the desired softening will be effected at the required rate without danger of scorching or otherwise harming the leather, and without appreciably moistening the atmosphere of the work-room.

In its broader aspects the invention is applicable to various forms of apparatus including those used for pulling over and 50 those used for lasting. Nevertheless, certain features of the illustrated apparatus are more particularly suited to the requirements

of conditioning the materials for lasting, and the invention will be described with special reference to such use.

It has been demonstrated in practice that the most satisfactory type of apparatus for the purposes above indicated is one in which the moist vapor is generated at or close to the treating station or stations, but when the apparatus is designed to treat a plurality of shoes simultaneously it is difficult, and in some cases impossible, to maintain uniformity in the quantity of vapor supplied to the several stations. Any considerable inequality in this respect militates against uniform pulling-over or lasting, as the case may be, and tends to produce surplus vapor. Accordingly, an object of this invention is to provide, in a treating apparatus for the purposes stated, improved means to insure uniform quantities, as well as uniform temperature, of vapor at each of a plurality of treating stations.

To this end the illustrated apparatus provides for generating an individual supply of vapor at each of a plurality of treating stations by heating small quantities of water only as vapor is needed, thereby avoiding losses and the humidifying result of maintaining a relatively large body of water at the boiling temperature. In relation to this aspect of the invention an object is to insure the delivery of equal but restricted quantities of water at each of the stations 85 where it is to be converted into vapor. A feature of the invention consists in a manifold for delivering individual supplies of water from a common source of supply to the several stations where the water is to be converted into vapor, and means for supplying water at negligible velocity and pressure through the manifold, the delivery nozzles of the manifold being preferably restricted to capillary proportions to insure 90 equality in the quantity of water emitted by the nozzles.

Another object is to obtain improved efficiency in the production of vapor with regard to the saving of time and heat. In this 100 respect a feature consists in the arrangement of the water-delivery nozzles in thermal relation to the heating means whereby the temperature of the water may be raised to the

boiling point while the water is in the nozzles, and further, in the arrangement of the nozzles to emit vapor directly against the toes of the shoes and thus to utilize the 5 pressure developed by the expansive action of the vapor in the nozzles to precipitate the vapor to the shoes.

Still another object of the invention is to provide improved means for insuring diffusion of the heat and vapor in cases where a direct and more rapid treatment is not so desirable. For this purpose a feature of the 10 invention consists in a housing of absorbent, refractory material, earthenware for example, having a work-receiving chamber. As shown, the apparatus is designed to utilize this type of housing and a non-absorbent housing interchangeably. The non-absorbent 15 housing affords a direct application of heat and moisture and more rapid treatment. The choice of housings may be determined according to the shoe materials or the preference of the user.

Again, an object of the invention is to 20 provide improved heating means whereby uniform temperature may be maintained at a plurality of treating stations at a minimum of cost. A novel feature relating to the heating means consists in a metallic tray 25 having depending flanges or ribs on its under side forming grooves or channels, and electric heating units arranged in said grooves or channels and in heat-conducting relation to said ribs. As shown, this tray 30 has a trough or channel shaped to conform to the water-nozzles, and the latter are arranged therein the better to utilize the heat to produce vapor.

Referring to the drawings:

40 Fig. 1 is a perspective view, partly broken away, of the metallic tray that forms the bottom of a series of enclosed treating stations.

45 Fig. 2 is a perspective view of a metallic bar constituting a duplex water-nozzle, said bar being one of a plurality arranged in heat-conducting relation to the element shown in Fig. 1 and having individual water passageways to divide the water into separate streams and to emit said streams at the 50 treating stations respectively.

Fig. 3 is a vertical section through the assembled apparatus including a metallic hood or housing to enclose the toes of the shoes. 55 The plane of this section is indicated by line III-III of Fig. 4.

Fig. 4 is a top plan view of the elements shown by Figs. 1 and 2 in their assembled relation.

60 Fig. 5 is a perspective view of the type of hood or housing included in Fig. 3.

Fig. 6 is a vertical section through an electric heating unit of the type for which the apparatus is designed.

Fig. 7 is a vertical section on a larger scale, through the structure intersected by line VII-VII of Fig. 4.

Fig. 8 is a front elevation of the assembled apparatus equipped with individual hoods or housings for the toes of the shoes instead of the type of housing shown by Figs. 3 and 5. These individual housings are made of absorbent, refractory material.

Fig. 9 is a perspective view, partly in section, of a portion of the apparatus shown by Fig. 8.

Fig. 10 is a vertical section through the structure intersected by line X-X of Fig. 8.

Fig. 11 is a perspective view of portions of the electric heating units and a portion of the element shown by Fig. 1.

With the exception of the two alternative types of housing for enclosing the toes of the shoes, the apparatus is the same in all the figures, but since there are certain considerations peculiar to the structure and effect of the two types of housing the apparatus will be described first with regard to the type shown by Figs. 3 and 5 and afterward with regard to the type shown by Figs. 8, 9 and 10.

Referring to Figs. 3 and 5, the housing 12 is made of metal, preferably sheet metal, and forms one elongated chamber having a horizontal series of openings 14 in its front wall and being open at the bottom throughout its length and width. The openings 14 are proportioned to receive the toes of the shoes individually with no more clearance than is necessary to facilitate the insertion of the toes. Each opening 14 therefore marks an individual treating station.

Although the housing 12 is open at the bottom the treating stations are enclosed by the housing and the element by which it is supported. This supporting element is a metal tray 16 and is preferably provided with an upstanding marginal flange 18 to maintain the housing in the desired position and to guard against overflow of water. A trough or channel 20 is formed in the upper side of the tray 16 to receive the bars or nozzles 22, as shown in Figs. 3, 4 and 7. The under side of the tray is formed with depending ribs or flanges 24 to provide grooves or channels for the reception of heating units of the type shown by Figs. 6, 9 and 10.

This type of heating unit is a well-known commercial article, and although made up of a plurality of parts it has the appearance of a straight bar or strip. The unit comprises a protective covering of sheet iron made in two parts including a strip 26 and a strip 28. The marginal portions 30 of the strip 26 are bent over the longitudinal marginal portions of the strip 28 to enclose the latter and to enclose strips 32 of insulating

material, such as mica, between which the electrical resistance element 34 is arranged. The metallic covering 26, 28 is thus maintained in heat-conducting relation to the resistance element 34, and when the units are arranged between the flanges 24 of the tray 16 they are maintained in heat-conducting relation to the tray, since the flanges are spaced apart only far enough to receive the units. The groove or channel 36 (Figs. 3, 7 and 10) is double width to receive two heating units, but the other grooves are proportioned to receive one unit each. The heating units are supported in their grooves by metal cross-bars 38 (Figs. 8, 10 and 11), fastened to the bottom of the tray by screws 40. The metallic coverings of the heating units are not so long as the resistance elements 34 and the strips 32 of insulating material which project at both ends beyond the metallic coverings, as shown in Figs. 9 and 11, to provide for circuit connections.

At one end all the resistance elements are electrically connected by a bus-bar or screw 42 (Fig. 9) but, at the other end four of them are connected by a bus-bar or screw 44 (Fig. 11), while the fifth is electrically separate from said bus-bar and is provided with an individual binding screw 46. This scheme of connections provides for regulation of the total heating effect by a three-way switch 48 (Fig. 8) as follows: In one position of the switch all the heating units may be turned off, in the second position current may be supplied to the group of four units connected by the bus-bar 44, while in the third position current may be supplied to all five of the units.

The apparatus is designed to generate individual supplies of vapor at the treating stations respectively, each individual supply of vapor being obtained by delivering a small quantity of water to the treating station and heating it to the boiling temperature. To insure equality with regard to the several individual supplies of vapor, equal individual supplies of water are delivered to the several points where it is to be converted into vapor. At the same time the individual supplies of water are restricted to the smallest quantities consistent with the quantities of vapor necessary. Accordingly, the water is supplied at a pressure and velocity so low as to be negligible. With this in view, the illustrated apparatus is designed to supply the water by gravity under an exceedingly small head of pressure.

As shown by Fig. 8, a water reservoir 50 is provided with a discharge spout 52 arranged to deliver water into a receiving funnel 54, the upper end of which is slightly above the level of the tops of the bars 22 by which the water is distributed to and emitted at the treating stations. The spout 52 is provided

with a valve 56 to regulate the rate at which the water may flow or drip into the funnel. According to the design shown, the funnel 54 is attached to a manifold comprising a pipe 58 through which the water flows to two branch pipes 60. Each of these branch pipes extends into the bottom of the tray 16 at a point midway between two treating stations. As shown by Fig. 7, each branch pipe 60 is screwed into a boss on the under side of the tray, thereby supplying water for two treating stations. As shown by Figs. 2 and 7, each distributing bar 22 is formed with a nipple 62 on its under side. This nipple is fitted tightly in a hole extending through the bottom of the trough 20 in register with the pipe 60 and forms a water-tight joint. Two individual water ducts 64 extend upwardly through the nipple to form communication with individual horizontal ducts 66 of equal length by which the water is conducted in opposite directions toward the ends of the bars. The outer ends of the horizontal ducts 66 communicate with vertical ducts or discharge ports 68 located in register with two adjacent treating stations. The water supplied to the funnel 54 of the manifold is thus divided first into separate streams by the pipe branches 60, 60, and each of these streams is subsequently divided into equal streams by the ducts in the distributing bars or nozzles 22.

It has been found in practice that when it is attempted to distribute relatively small individual quantities of water at extremely low pressure to a plurality of stations, it is impossible to maintain equality of delivery when the distribution is dependent upon gravity alone. For example, when the tray 16 is not exactly level, the discharge ports 68 will be at different levels and this will cause more water to flow from the lowest discharge port than from those at higher levels. Again, even when the discharge ports 68 are all at the same level, the surface tension of the water flowing along the surfaces forming the several passageways is unequal. This may be due to dirt, grease, scale, or other cause, but whatever the cause, it makes the flow unequal and results in unequal quantities of vapor. It has also been found in practice that this tendency toward inequality of discharge, even when the ports 68 are at slightly different levels, may be counteracted by making the ducts in the distributing bars 22 of capillary size as well as equal proportions, and this constitutes one of the novel features of the present invention.

Assuming that the metallic housing 12 is in use, as shown by Fig. 3, the preferred mode of using the apparatus is to restrict the discharge of water from the reservoir 50, so that the water will drip instead of

- run in a continuous stream. The dripping will supply enough water for four treating stations. The distributing bars or nozzles 22 are maintained at a temperature above the boiling temperature, and since the water-ducts formed in them are so small and the passage of water through them is so slow, most of the water in the nozzles is converted into vapor before it reaches the discharge ports 68. Then the pressure developed by the expansive action of the vapor produces a spouting effect which causes the vapor to travel with considerable velocity from the ports to the shoes overhanging them. If any water overflows the ports 68 it runs into the trough 20 and is almost immediately converted into vapor, having been raised nearly, if not quite, to the boiling temperature before it is emitted.
- 20 To give the distributing bars or nozzles 22 the highest possible temperature said bars and the trough 20 are shaped to conform to each other. As shown, the bars and trough are rectangular in cross-section and the bottoms of the bars are heated by conduction while the two upright sides are further heated by radiation from the corresponding surfaces of the trough which are very close. Additional heat for treating the work is radiated from the tray 16 and in a lesser degree from the housing 12 which is in heat-conducting relation to the tray.
- Although the preferred mode of use is to restrict the supply of water to a point that will cause the greater proportion, if not all of it, to be converted into vapor before it reaches the discharge ports 68, it is obvious that a greater quantity may be discharged by opening the valve 56 to a greater extent.
- 40 In the latter case the rate of flow through the distributing bars 22 may be so rapid that little, if any, vapor will be generated in the bars. Then the water will overflow the bars and be converted into vapor by direct contact with the heated tray 16. The capacity of the tray to hold water and its heating capacity are sufficient to prevent overflowing the tray unless a deliberate attempt is made to do so.
- 50 If the character of the work is such as to require it, or if the user prefers, the treatment may be tempered by substituting the type of housing shown in Figs. 8, 9 and 10 for that shown in Figs. 3 and 5. As shown by Fig. 8, four individual housings 70, one for each shoe, are arranged in a series corresponding, in point of location, to the four stations marked by the openings 14 formed in the housing 12. Each housing 70 forms a treating chamber which is open in front to receive the toe of the shoe. The bottom of each housing has an opening to receive the heat and vapor. These housings are made of some suitable porous, refractory material, for example earthenware, and in operation

they absorb moisture from the vapor and subsequently exude the vapor so absorbed. To develop the absorption of vapor to a high degree, each unit 70 is formed with a horizontal partition 72 by which a vapor-receiving chamber is provided under the treating chamber. This partition is preferably provided with small ducts 74 through which some of the vapor may rise without being absorbed. The moisture absorbed by the partition 72 and the portions below it is diffused by capillary action throughout the upper part of the unit, and since the latter is heated to a considerable temperature by the tray 16 upon which it stands a soft and even exudation of vapor passes from the upper part or cowl portion of the unit to humidify the treating chamber formed thereby. A shoe toe occupying the chamber is therefore entirely enveloped by vapor in a nearly inert state.

The illustrated units 70 are provided with localized coatings 76 of glaze. Because of the difficulty of illustrating glaze, heavy lines are used in Figs. 8, 9 and 10 to represent the glazed surfaces, while light lines represent the unglazed surfaces. It will therefore be observed that all the exterior surfaces are glazed while the interior surfaces forming the treating chambers and vapor-receiving chambers are unglazed. By reason of this localization of glaze the exudation of vapor is confined to the interior surfaces forming the treating chambers and at the same time the glazed surfaces tend to minimize the loss of heat by external radiation. Accordingly, the greater part of heat radiated by the units 70 is radiated by the internal surfaces forming the treating chambers.

In some cases the desired treatment may be effected by restricting the supply of water, as hereinbefore explained in connection with the use of the metallic housing 12, but if a greater degree of moisture is desired the valve 56 may be adjusted to maintain a shallow body of water in the tray 16. In this case the bottoms of the porous units 70 will stand in water and the upper parts of the units will be maintained in a condition of complete saturation.

The illustrated apparatus includes a stand by which the tray 16 and the shoes may be supported. As shown by Figs. 8 and 10, the stand comprises uprights 80 and a pan 82. The pan is formed with upstanding flanges 84 to support the tray 16 with the least loss of heat, and for this purpose the tray is formed with lugs 86 formed to hook over and rest upon said flanges. No other part of the tray touches the supporting means and the tray is therefore insulated thermally. If desired, the tray may be securely bound to the pan 82 by a connecting screw 87, a single screw being sufficient for the

purpose and preventing any considerable loss of heat by conduction from the tray to the pan.

A portion 88 projecting from the front of the pan (Figs. 3 and 10) affords anchorage for a vertically adjustable work support 90. This work support, as shown, is a board long enough to support four shoes side by side at the four treating stations. A bracket 92 is fastened to the bottom of the board and is designed to be clamped against the front of the portion 88. For this purpose a vertical slot 94 is formed in the bracket to receive a clamping screw 96, said screw extending through a hole in the portion 88 and being provided with a nut 98 to produce the clamping effect.

Having thus described my invention, what I claim as new and desire to secure by Letters Patent of the United States is:

1. An apparatus for treating shoe materials comprising heat-radiating means, means forming a series of individual treating stations arranged in the field of heat adjacent to said heat-radiating means, nozzles arranged to emit individual jets of fluid at said stations respectively, said nozzles being in thermal relation to said heat-radiating means, and means to supply water to said nozzles.

2. An apparatus for treating shoe materials comprising means forming a treating station, a nozzle arranged to emit a jet of fluid toward and adjacent to an article of work at said station, means to supply water to said nozzle, and heating means arranged to radiate heat to the work and to heat said nozzle to convert some or all of the water therein into vapor.

3. An apparatus for treating shoe materials comprising means forming a series of treating stations side by side, a series of nozzles arranged to emit individual jets of fluid adjacent to the articles of work at said stations respectively, means to supply water to said nozzles, and heating means arranged to heat said nozzles to convert some or all of the water in them into vapor and to catch any water that overflows them.

4. An apparatus for treating shoe materials comprising means forming a treating station, a nozzle arranged to emit a jet of fluid upwardly toward the underside of an article of work at said station, means to supply water to said nozzle, and heating means arranged to heat said nozzle to convert some or all of the water therein into vapor and to catch and vaporize any water that overflows said nozzle.

5. An apparatus for treating shoe materials comprising means for supporting an article of work for treatment, a nozzle arranged to emit a jet of fluid under and adjacent to the work, means to supply water to said nozzle by gravity from a level slightly

above the outlet of the nozzle, and heating means arranged to heat said nozzle to convert some or all of the water therein into vapor.

6. An apparatus for treating shoe materials comprising a heat-radiating tray, a plurality of nozzles arranged on said tray to be heated thereby, means to supply water to said nozzles to be converted into vapor by the heat of said tray, and means to support a plurality of articles of work for treatment adjacent to but out of contact with said tray and nozzles.

7. An apparatus for treating shoe materials comprising a metal tray adapted to hold water, electric heating elements embedded therein, nozzles arranged upon said tray to be heated thereby, means to supply water to said nozzles by gravity from a level slightly above the outlets of said nozzles, and means to support a plurality of articles of work over said outlets respectively.

8. An apparatus for treating shoe materials comprising a metal tray, means forming a series of work-treating stations arranged to stand in said tray, heating means arranged to heat said tray, and means to supply equal individual streams of water at negligible velocity to said stations respectively, the delivery portions of the latter said means being in heat-conducting relation to said tray to vaporize some or all of the water before it is emitted.

9. An apparatus for treating shoe materials comprising a metal tray, chamber-forming means arranged to stand on said tray and having a series of openings to receive the toes of shoes individually, said means being open at the bottom to receive heat and vapor from said tray, means to emit individual supplies of water in said tray in register respectively with the stations to be occupied by the toes of the shoes, and means to heat said tray for the purpose of converting said individual supplies of water into individual supplies of vapor.

10. A shoe-treating apparatus comprising means forming a horizontal series of enclosed treating stations having openings to receive the toes of shoes individually, means to heat the bottom of the first said means, means arranged to supply water at negligible pressure through said bottom, and means in heat-conducting relation to said bottom to divide the water into equal streams and emit said streams at points in register with said openings respectively.

11. A shoe-treating apparatus comprising a substantially horizontal heat-radiating plate, means to support a series of articles of work in overhanging relation to said plate, and means to supply water at negligible pressure to be converted into vapor, the latter said means including a manifold to divide a stream of water into a plurality of

- equal smaller streams, said manifold comprising distributing nozzles arranged on the upper surface of said plate to be heated by the latter.
12. A shoe-treating apparatus comprising a substantially horizontal heat-radiating plate having a trough or channel in its upper surface, means to support a series of shoes side by side so that their toe portions overhang said plate, and means to supply water at negligible velocity and pressure to be converted into vapor under said toe portions, the latter said means including a manifold to divide a stream of water into a plurality of equal smaller streams, said manifold having delivery nozzles arranged in said trough to be heated by contact with said plate.
13. A shoe-treating apparatus comprising a substantially horizontal heat-radiating plate, means to support a series of shoes side by side so that their toe portions overhang said plate, and means to supply water at negligible velocity and pressure to be converted into vapor under said toe portions, the latter said means including a plurality of discharge nozzles lying on said plate to be heated thereby.
14. A shoe-treating apparatus comprising a substantially horizontal heat-radiating plate, means to support a series of shoes side by side so that their toe portions overhang said plate, and means to supply water at negligible velocity and pressure to be converted into vapor under said toe portions, the latter said means including a plurality of discharge nozzles lying on said plate to be heated thereby, and the outlet ports of said nozzles being arranged to discharge upwardly.
15. A shoe-treating apparatus comprising a metal tray, means arranged to heat it, means arranged to supply individual and equal streams of water by gravity through the bottom of said tray and thence horizontally through ducts of equal length in heat-conducting relation to the bottom of the tray, said ducts having emission ports, and means forming a plurality of enclosed treating stations above and adjacent to said ports.
16. A shoe-treating apparatus comprising means forming a series of enclosed treating stations having openings to receive the toe portions of shoes, a metal tray supporting said means, means to supply water by gravity through the bottom of said tray, means to distribute the water and discharge it in equal quantities at points under and in register with said stations respectively, and means to heat said tray for the purpose of converting the water into hot moist vapor.
17. An apparatus for treating shoe materials comprising a metallic nozzle having a water-duct of capillary size, means to supply water at negligible pressure to said duct, heating means arranged to heat said nozzle to convert some or all of the water into vapor, and means to support the work adjacent to the outlet of said nozzle and in the field of vapor.
18. An apparatus for treating shoe materials comprising a metallic nozzle having a water-duct of capillary size, means to supply water through said duct at negligible pressure, heating means arranged to heat said nozzle and vaporize any water emitted therefrom, and means to support the work adjacent to the outlet of said nozzle and in the field of vapor.
19. In an apparatus comprising means for supplying heat and moist vapor to treat shoe materials, an element of absorbent, refractory material having a porous surface arranged to absorb heat and vapor supplied by said means, said element also having a cowl portion to enclose the work and to diffuse heat and exude vapor to the work.
20. In an apparatus comprising means for supplying heat and moist vapor to treat shoe materials, an element of absorbent, refractory material having a porous surface arranged to absorb heat and vapor supplied by said means, a porous surface to diffuse heat and exude vapor to the work, and a non-porous surface to localize the exudation of vapor at the latter said porous surface.
21. In an apparatus comprising means for supplying heat and moist vapor to treat shoe materials, an element of absorbent, refractory material having a porous surface arranged to absorb heat and vapor supplied by said means, said element also having a cowl portion to enclose the work and to diffuse heat and exude vapor to the work, the external surface of said cowl portion being non-porous.
22. In an apparatus comprising means for supplying heat and moist vapor to treat shoe materials, an element of absorbent earthenware having a portion arranged to absorb heat and vapor from said means, and a portion to enclose the work and to exude vapor thereto.
23. In an apparatus comprising means for supplying heat and moist vapor to treat shoe materials, an element of absorbent earthenware having a portion arranged to absorb heat and vapor from said means, and a portion to enclose the work and to exude vapor thereto, the exterior surface of the latter said portion being glazed.
24. In an apparatus comprising means for supplying heat and moist vapor to treat shoe materials, a hollow element of absorbent, refractory material having a porous surface arranged to absorb heat and vapor supplied by said means, and a porous internal surface to diffuse heat and exude vapor to treat the work enveloped thereby.
25. In an apparatus comprising means for

- supplying heat and moist vapor to treat shoe materials, a hollow element of absorbent, refractory material having a chamber to receive the vapor, a work-receiving chamber, and a partition separating said chambers, the internal surface forming the first said chamber being porous to absorb vapor and the internal surface forming said work-receiving chamber being porous to exude vapor to the work enveloped thereby. 10
26. In an apparatus comprising means for supplying heat and moist vapor to treat shoe materials, a hollow element of absorbent, refractory material having a chamber to receive the vapor, a work-receiving chamber, and a partition separating said chambers, the internal surface forming the first said chamber being porous to absorb vapor and the internal surface forming said work-receiving chamber being porous to exude vapor to the work enveloped thereby, the external surface of said element being non-porous. 15
27. In an apparatus comprising means for supplying heat and moist vapor to treat shoe materials, a hollow element of absorbent, refractory material having a chamber to receive the vapor, a work-receiving chamber, and a partition separating said chambers, the internal surface forming the first said chamber being porous to absorb vapor and the internal surface forming said work-receiving chamber being porous to exude vapor to the work enveloped thereby, said element having one or more passageways through which vapor may flow from the first said chamber to said work-receiving chamber. 20
28. In an apparatus for treating shoe materials, comprising a metallic receptacle, means for supplying water thereto, and heating means arranged to vaporize the water so supplied, an element of refractory, absorbent material arranged to absorb heat and vapor generated by said heating means, said absorbent element having a cowl portion forming a work-receiving chamber. 25
29. In an apparatus for treating shoe materials, comprising heat-radiating means, and means to supply water thereto to be vaporized, an element of refractory, absorbent material arranged to be supported by said heat-radiating means, said element forming a work-receiving chamber and having a porous surface arranged to absorb vapor and a porous surface to exude vapor to treat the work. 30
30. In an apparatus comprising means for supplying heat and moist vapor to treat shoe
- materials, an element of refractory, absorbent material arranged to be heated by said means and to absorb vapor, said element having a portion formed to overhang the work, and the work-confronting surface of said overhanging portion being porous to exude vapor to treat the work. 60
31. In an apparatus comprising heat-radiating means and regulatable means to supply water at a constant but variable rate to said heat-radiating means to be vaporized thereby, an absorbent, refractory element arranged to be heated by the first said means and to absorb vapor generated thereby, said element having a cowl portion forming a work-receiving chamber the internal surface 70 of which is porous to exude vapor to the work. 75
32. A treating device consisting of a housing of absorbent, refractory material having a work-receiving chamber, the internal surface forming said chamber being porous to exude vapor. 80
33. A treating device consisting of a housing of absorbent, refractory material having a work-receiving chamber, the internal surface forming said chamber being porous to exude vapor and the external surface being nonporous. 85
34. A treating device consisting of a housing of absorbent, refractory material having a work-receiving chamber and a chamber to receive heat and moist vapor. 90
35. A treating device consisting of a housing of absorbent, refractory material forming a work-receiving chamber and a chamber to receive heat and moist vapor, the surface forming the latter said chamber being porous to absorb heat and vapor, and the surface forming the first said chamber being porous to exude vapor and diffuse heat to the work. 95
36. A treating device consisting of a hollow element of earthenware forming a work-receiving chamber and a chamber to receive heat and vapor, the internal surfaces forming said chambers being porous and the external surface of said element being glazed. 100
37. A treating device consisting of a hollow element of absorbent, refractory material forming two chambers, one above the other, and having a horizontal partition separating them, the internal surfaces forming said chambers being porous and the external surface of said element having a coating of non-porous, vitreous substance. 110
- In testimony whereof I have signed my name to this specification. 115
- FREDERICK M. FURBER.
